SHEET RUBBER ARTICLE

Paul Van Cleef, Chicago, Ill., assignor, by meane assignments, to Van Cleef Bros., Chicago, Ill., a partnership consisting of Noah Van Cleef, Felix Van Cleef, and Paul Van Cleef

Application June 21, 1934, Serial No. 731,653

3 Claims. (Cl. 154—2)

The present invention relates generally to sheet rubber articles. More particularly the invention relates to that type of sheet rubber article which serves as a piece or item of clothing and is adapted to be worn by the wearer around a portion of his or her body to afford protection against the elements in wet or dry weather.

One object of the invention is to provide an article of this type which is less likely to tear or rip than previously designed articles of the same general character by reason of the fact that the margin thereof which is designed to encircle the wearer's body and operates in a measure as the supporting means for the article, embodies a longitudinally extending strip of fabric which is secured substantially permanently in place by a strip or facing of raw rubber on its inner face and serves as a reinforcing instrumentality for the article.

Another object of the invention is to provide an article of clothing of the last mentioned character in which the fabric strip which is applied to the supporting margin is folded around the latter so that it forms a facing for the inner and outer faces of the supporting margin and thus prevents contact of the rubber at the supporting margin of the article with the skin or body of the wearer of the article.

A further object of the invention is to provide an article of the type and character under consideration in which the fabric, margin-reinforcing strip is in the form of Jersey cloth or like material and is arranged as far as its weaving or thread arrangement is concerned so that it is highly elastic in its longitudinal direction and is relatively inelastic in its transverse direction and hence permits of lengthwise stretching only of the supporting margin of the article.

A still further object of the invention is to provide a simple and improved method of fabricating sheet rubber articles and applying fabric strips to certain margins of such articles.

Other objects of the invention and the various advantages and characteristics of the present sheet rubber article and its method of manufacture will be apparent from consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a plan view of a sheet rubber rain cape embodying the invention;

Figure 2 is an enlarged plan view of the neck portion of the cape showing in detail the arrangement of the cloth strip which serves as a reinforcing medium for the neck-engaging margin of the cape;

Figure 3 is a fragmentary perspective illustrating the manner in which the fabric strip is applied to the neck-engaging margin of the cape;

Figure 4 is a perspective showing how the raw rubber film or strip on the inner face of the reinforcing fabric strip is rolled into contact with the rubber which forms the neck-engaging margin of the cape; and

Figure 5 is a fragmentary plan view showing the manner in which the fabric strip is arranged as far as its weaving or thread arrangement is concerned so that it is elastic in its longitudinal direction and relatively inelastic in its transverse direction.

The invention is illustrated in connection with a cape 6 which is formed from sheet rubber and is adapted to be worn around the shoulders in wet or stormy weather as protection against the elements. As shown in Figure 1 of the drawing, the cape 6 is substantially semi-circular and embodies a curved neck-engaging margin 7. The latter is designed to encircle the neck of the wearer. A pair of snap fasteners 8 are applied to the margin 7 and serve to hold the cape in place. These fasteners consist of stud-carrying parts 9 at one end of the neck-engaging margin 7 and complementary or socket parts 10 at the other end of the margin. The two fasteners are spaced apart and operate to hold the side margins of the cape in over-lapped relation during use of the cape. The side and bottom margins of the cape are doubled back and crimped as shown in Figure 2 in order to reinforce the edges and prevent tearing or ripping. The neck engaging margin 7 of the cape is provided with a fabric strip 11. This strip is formed of "jersey" cloth, "eider down" or any like material and extends from one end of the neck engaging margin 7 to the other. As shown in Figure 2 the strip 11 is folded around the margin 7 so that both faces of the latter are covered by the strip. The folding is preferably such that the width of the portion on the outer face of the cape is approximately twice that of the portion on the inner face of the cape. A thin facing 12 of rubber is applied to the inner face of the fabric strip 11 and serves substantially permanently to hold the latter in place. The fabric strip is preferably ar-

ranged so that the plain face is on the inside and the nap is on the outside. The rubber facing 12 completely covers the inner or plain face of the strip 11 and is secured to the adjacent portions of the neck-engaging margin 7 by a film 13 of rubber cement. If the fabric strip 11 is formed of "jersey" cloth or "eider down" (see Fig. 5) or any like material which is highly elastic or stretchable in one direction and is relatively inelastic in the other direction, the strip is cut as far as weaving or thread arrangement is concerned so that it is highly elastic in its longitudinal direction, that is, lengthwise thereof, and is relatively inelastic in its transverse direction. As a result of this arrangement of the strip 11 the neck-engaging margin 7 of the cape may be stretched lengthwise thereof. If the strip 11 is formed of a square close woven fabric, it is cut on the bias so that it is stretchable lengthwise. The strip serves as a reinforcement for the margin 7 and prevents the latter from being torn or ripped. It further serves to prevent contact of the rubber at the neck-engaging margin with the wearer's neck. This feature is of importance in cold weather because of the coldness of the rubber. By reason of the fact that the neck-engaging margin 7 is reinforced by and covered with the fabric strip 11 there is no likelihood of the neck-engaging margin 7 binding or otherwise injuring the wearer's neck in the event that the margin is stretched during application of the cape and then released. The parts 9 and 10 of the snap fasteners 8 extend through the textile fabric strip 11 and the rubber attaching strip 12 as shown in Figure 2 and are preferably applied or secured in place after application of the strip 11 to the neck-engaging margin 7.

In fabricating the cap 6 a piece of raw rubber in the form of a calendered sheet is cut out by way of a pattern so that it corresponds in shape or form to that desired for the cape. After cutting the sheet into the proper form the side and bottom margins are doubled back and crimped by any suitable means. The pressure exerted during the crimping operation is sufficient ordinarily to press together into fused relation the contiguous portions of the rubber sheet and to hold these portions in place. After the crimping operation, the neck engaging margin 7 of the raw rubber sheet is prepared for the attachment of the fabric strip 11 by spreading rubber cement over it to form the film 13. The fabric strip 11 is prepared by spreading a facing of raw rubber on the plain side of the strip. After preparation of the strip 11 and before solidification of the film 13 of rubber cement, the fabric strip is attached to the neck-engaging margin 7 of the raw rubber sheet by folding it around the margin and so that the facing 12 engages the film 13 of rubber cement. After the strip 11 is folded in place a roller (see Figure 4) is applied to it so as to press the raw rubber facing 12 into firm contact with the rubber cement on the margin 7. After the rolling operation the cape is placed in a tumbler (not shown) and is subjected to sulphur chloride fumes in order to cure or vulcanize the rubber. At the conclusion of the curing operation, the cape is subjected to ammonia vapor so as to remove excess sulphur chloride fumes and

prevent over vulcanization. The cape is finished by dusting it with powdered starch.

The herein disclosed cape is extremely durable by reason of the fact that the side and bottom margins are doubled over and crimped and the neck-engaging margin 7 is protected and reinforced by the fabric strip 11. The latter, as previously pointed out, not only prevents tearing or ripping of the margin 7, but adds to the wearer's comfort by preventing contact of the rubber at the margin 7 with the neck of the wearer of the article.

Whereas the invention has been described in connection with a cape, it is to be understood that it may be used in connection with other sheet rubber articles. It is also to be understood that the invention is not to be restricted to the details set forth, since these may be modified within the scope of the appended claims, without departing from the spirit and scope of the invention.

Having thus described the invention, what I claim as new and desire to secure by Letters Patent, is:

1. A new article of manufacture comprising a sheet of calendered rubber, a strip of textile fabric highly elastic in its longitudinal direction and relatively inelastic in its transverse direction extending longitudinally along and folded around one of the margins of the sheet, and means for securing the strip to said one margin of the sheet consisting of a comparatively thin facing of rubber on and coextensive with the inner face of the strip and a film of rubber cement between the facing and the strip-covered face portions of the sheet, both vulcanized after application to the strip and sheet respectively and together with the sheet so as to bond or unite them together and connect substantially permanently the strip to the sheet.

2. That improvement in the manufacture of sheet rubber articles which comprises applying a film of rubber cement to the inner and outer faces of one margin of a calendered sheet of raw rubber, then spreading a comparatively thin coextensive facing of raw rubber on one side of a fabric strip which is highly elastic lengthwise and relatively inelastic transversely, then folding the strip lengthwise around said one margin of the sheet so that the facing engages the film of rubber cement, and finally curing the sheet, film, and facing so as substantially permanently to bond or unite the strip to the sheet.

3. That improvement in the manufacture of sheet rubber articles which comprises applying a film of rubber cement to the inner and outer face of one margin of a calendered sheet of raw rubber, then spreading a comparatively thin coextensive facing of raw rubber on the plain side of a strip of "jersey" cloth which is highly elastic lengthwise and relatively inelastic transversely thereof, then folding the strip lengthwise around said one margin of the sheet so that the facing engages the film of rubber cement, then applying pressure to the strip so as to press the raw rubber facing into firm contact with said film of cement, and finally vulcanizing the sheet, film, and facing so as substantially permanently to bond or unite the strip to the sheet.

PAUL VAN CLEEF.
